UNITED STATES PATENT OFFICE.

MAX BARTHOLDY, OF ESSEN, GERMANY, ASSIGNOR TO FRIED. KRUPP AKTIEN-
GESELLSCHAFT, OF ESSEN-ON-THE-RUHR, GERMANY.

SIGHTING DEVICE.

1,364,021.

Specification of Letters Patent. Patented Dec. 28, 1920.

Application filed September 4, 1920. Serial No. 408,394.

To all whom it may concern:

Be it known that I, MAX BARTHOLDY, residing at Essen, Germany, a citizen of the German Republic, have invented certain new and useful Improvements in Sighting Devices, of which the following is a specification.

This invention relates to sighting devices which are mounted on a member which takes part in the elevation movement of the gun barrel, and are provided with an arrangement for allowing for influences which, such as erosion of the gun barrel for example, may cause a variation in the normal range of the gun. The object of the invention is to provide for such arrangement a construction which shall be as simple as possible and therefore most useful for military purposes.

The invention will be described with reference to the accompanying drawings, which show two constructions of the present invention.

Figure 1 is a side elevation, partially in section, of the first construction of sighting device together with the adjacent parts of the gun,

Fig. 2 is a plan view corresponding to Fig. 1, partially in section, and

Fig. 3 is a view corresponding to Fig. 1 with certain parts in another position,

Fig. 4 is a detail of Fig. 1, shown in section, and on a larger scale,

Fig. 5 is a section on the line 5—5 of Fig. 4 looking from the left.

Figs. 6 to 13 relate to the second construction of sighting device, and of these,

Fig. 6 is a side elevation corresponding to Fig. 1,

Fig. 7 is a plan view corresponding to Fig. 6 partially in section,

Fig. 8 is a view corresponding to Fig. 6 with certain parts in another position,

Fig. 9 is the right-hand end view corresponding to Fig. 6, partially in section, on the line 9—9 of this figure.

Figs. 10 to 13 are sections on the lines 10—10, 11—11, 12—12, and 13—13 of Fig. 8.

The first construction will be described first.

Referring to the drawings, on the slide carrier A, which is constructed as an annular body and in which the gun barrel is guided in the usual way, there is mounted parallel with the axis of the horizontal trunnions a^1 , a pin a^3 by means of an arm a^2

rigidly attached to the slide carrier. On this pin a^3 are pivotally mounted two rods B and C situated opposite to each other, the lower rod B carrying on its free end an attachment bar B^1 , which is sector-shaped and curved concentrically with the axis of the pin a^3 and is guided in an attachment sleeve a^4 mounted on the slide carrier A, while the upper bar C carries a sighting telescope C^1 which determines the direction of the sighting line. The attachment bar B^1 is adjusted to the angle which corresponds to the range of the target by means of an adjusting pinion D, which is mounted in the attachment sleeve a^4 and provided with a milled head d^1 , and engages with a series of teeth b^2 on the attachment bar B^1 . On the attachment sleeve a^4 is also provided a bar a^5 (see Figs. 1 and 3) provided with a range graduation a^6 , the corresponding reading-off mark b^3 being placed on the attachment bar B^1 . On the lower bar B are provided two lugs E rigidly connected thereto, which are arranged like a fork, as shown in the drawings, and between which a rocking lever F is adjustably mounted on two pins e^1 and e^2 . This rocking lever F has in it a slot f^1 curved as the arc of a circle, in which is guided a sliding piece G which consists of two parts connected together by a pivot bolt g^1 . This sliding piece G is connected by the pivot bolt g^1 to one end of a connecting rod H, the other end of which is connected by a pivot bolt c^2 to the upper bar C. To the connecting rod H is attached a second connecting rod J, the other end of which is connected by means of the arm a^2 to the slide carrier A. The length of the connecting rod H is equal to the radius of curvature of the slot f^1 in the rocking lever F, so that this latter, as shown in Figs. 1 and 4, can be brought into an angular position with respect to the bar B, in which its axis of curvature coincides with the axis of rotation of the pivot bolt c^2 . The arrangement is also so contrived that when the bars B and C and the rocking lever F are in the position shown in Figs. 1 and 4, in which, on the one hand, the sighting line of the sighting telescope C^1 is parallel with the longitudinal axis of the gun barrel; and on the other hand, the axis of curvature of the rocking lever F coincides with the axis of rotation of the pin c^2 ; the axis of oscillation (the axis of the pins e^1 and e^2) of the rocking

100

105

110

- lever F coincides with the axis of the pin g^1 . The rocking lever F is adjusted by means of a worm K, which is provided with an operating device k^1 , and is mounted on the lower end of the lug E and engages with a series of worm teeth f^2 on the rocking lever F arranged sectorwise. The angular position imparted to the rocking lever F by means of the operating device k^1 is read off by means of a mark m^2 (see Figs. 1 and 3), which is situated on a disk M pivotally connected to the rocking lever F by a spur wheel gearing $m^1 f^3$ (see Figs. 4 and 5), and is opposite an angle graduation e^3 which is situated on a part e^4 (see Fig. 5) rigidly attached to one of the lugs E.

The description of the working of the sighting device will be commenced when the position of the parts are as shown in Figs. 1 and 4, in which position the sighting telescope is set to the zero of the range of the target and the rocking lever F is secured with respect to the rod B in that position in which its axis of curvature coincides with the axis of rotation of the pivot bolt c^2 . When using the sighting device, the attachment bar B^1 is adjusted to the elevation corresponding to the range of the target by rotating the milled head d^1 . This adjustment of the attachment bar B^1 is taken up by the bar C, which rotates about the same axis because it is pivotally connected with the attachment bar B^1 by the gearing members F G H J. The connecting rod J also rotates the connecting rod H in the direction of the arrow x (see Fig. 1) about the axis of the pivot pin c^2 , the sliding piece G changing its position in the slot f^1 in the rocking lever F. As, however, the axis of curvature of the recess f^1 coincides with the axis of rotation of the pin c^2 when the rocking lever F is in the position stated, the gearing members J H G g^1 F cause no change in the angular adjustment imparted to the bar C by means of the gearing D b^2 . The bar C, and consequently also the telescope C¹, which determines the direction of the sighting line, always rotates therefore when the rocking lever F is in the angular position stated, through the same angle as the attachment bar B^1 .

If, however, the initial velocity of the projectiles has become lessened by erosion of the gun barrel for example, the rocking lever F is rotated by means of the operating device k^1 in the direction of the arrow y (see Fig. 3), until the mark m^2 is opposite the division mark of the graduation e^3 which corresponds to the diminished initial velocity. The result of this is that the gearing J H G g^1 F augments the angle of adjustment imparted to the sighting telescope C¹ by means of the gearing D b^2 , by an amount which corresponds to the diminished initial velocity. When the sighting tele-

scope is adjusted to the angle corresponding to the zero of the range of the target, this amount is itself equal to zero, as the axis of oscillation of the rocking lever F coincides, when the attachment bar B^1 is adjusted to 70 correspond to the zero of the range of the target, with the axis of the pivot pin g^1 , and increases with the increasing angle of adjustment.

The special advantage of the sighting device described, consists in the fact that the gearing which is provided for allowing for the influence of the diminished initial velocity, is of a simple construction and therefore useful for military purposes, and 80 in which any particular curved surfaces which are difficult to make are avoided, and the use of ordinary attachment sighting devices is rendered possible without further alterations.

The second constructional of the present invention shown in Figs. 6 to 13, is distinguished by the fact that in the arrangement for allowing for the influences which may be brought about by a change in the 90 normal range of the gun, the wear of the several moving parts is reduced to a minimum.

The arrangement of the bar B with the attachment bar B^1 and the bar C with the 95 sighting telescope C¹, is, apart from a few constructional details which are unimportant in so far as this invention is concerned, the same as in the first construction of the present invention and need not therefore be more fully described. It need only be mentioned that the range graduation b^4 is not arranged, as in the first construction, on a member (a^5) fixed to the slide carrier A, but on the attachment bar, and the reading-off mark a^6 coöperating therewith is correspondingly arranged on the attachment sleeve a^4 . Furthermore, the rocking lever F, with its slot f^1 and the sliding piece G guided therein, is arranged, as in the first 100 construction, between two lugs b^5 corresponding to the lugs E, and is pivotally mounted on the bar B by means of two pins e^1 and e^2 . This sliding piece G is also connected to the bar C by a connecting rod of 110 the above given length. The pivot bolts which serve to connect the connecting rod H with the sliding piece G and the bar C, are likewise denoted by g^1 and c^2 as in the first construction.

Whereas, however, in the first constructional example the rocking lever F can be secured in different angular positions with respect to the lugs E on the bar B by means of worm gearing, in the second construction 125 it is adapted to rotate relatively to the lugs b^5 on the bar B which correspond to the lugs E, when the bar B is adjusted and is positively guided by means of the connecting rod which is composed of three parts J¹ J² 130

and J^3 which can be adjusted relatively to each other. This connecting rod $J^1 J^2 J^3$ is, like the connecting rod J of the first construction, connected to the slide carrier A , 5 but is not attached, as in the first constructional example, to the connecting rod H , but to the rocking lever F . In order that the positive action of the adjusting apparatus may not be lost by the movement of the 10 rock lever F when the sighting device is being adjusted, there is mounted on the said rocking lever a self-locking worm L , which is provided with a milled head and gears into a series of teeth g^2 on the sliding piece 15 G , and by means of which the said sliding piece G can be secured in various angular positions in the recess f^1 . The adjustment imparted to the sliding piece G is read off by means of a pointer g^3 (see Figs. 8 and 20 12), which is connected to the sliding piece by a pin g^4 (see Fig. 12), and is situated opposite a graduation f^4 (see Fig. 8) arranged on the rocking lever F . A slot f^5 (see Fig. 8) is provided in the rocking lever 25 for the pin g^4 .

The connecting rod $J^1 J^2 J^3$ is attached to the slide carrier by a sleeve n^3 , which consists of a bolt N (see Fig. 10) and acts as a pivot pin for the connecting rod. The bolt 30 N can be moved in straight guides p^1 (see Figs. 6, 8 and 10) which are provided for the stem of the bolt, and a square head n^1 (see Fig. 10) on the bolt in a plate P . The sleeve n^3 bears against this plate P , and 35 also against a nut n^2 screwed onto the bolt N , so that the bolt can be secured relatively to the plate P by tightening up the nut n^2 . The plate P is adapted to move at right angles to the longitudinal direction of the 40 guides p^1 on a plate R attached to the slide carrier A . For this purpose guide slots p^2 are provided in the plate P for bolts S which engage in the plate R with a square head s^1 (see Fig. 10) and carry nuts e^2 by 45 means of which the plate P can be secured relatively to the plate R . This arrangement enables the bolts N to be adjusted in different parallel positions to each other. Furthermore, for the purpose of making the 50 connecting rod $J^1 J^2 J^3$ adjustable in length, the part J^3 thereof, which embraces the parts J^1 and J^2 thereof like a sleeve, is provided with longitudinal slots i^4 (see Figs. 6 and 8) for bolts T (see particularly Fig. 55 11), which bolts T are passed through apertures in the parts J^1 and J^2 of the connecting rod, and carry a head t^1 (see Fig. 11) and a nut t^2 .

The description of the working of the 60 sighting device will be commenced when the position of the parts are as shown in Fig. 6, in which the telescope C^1 is adjusted to the zero of the range graduation, and the rocking lever F and the sliding piece G are situated in that position in which the axis of 65

curvature of the guide f^1 coincides with the axis of the pivot bolt c^2 , and the axis of the pins e^1 and e^2 with the axis of the bolt g^1 . When using the sighting device, the attachment bar B^1 is adjusted to the elevation 70 which corresponds with the range of the target, by rotating the milled head d^1 . This adjustment of the attachment bar is taken up by the bar C which rotates with it about the axis of the pin a^3 , since the axes of the 75 bolts g^1 and of the pins e^1 and e^2 cannot alter the above described relative position, and in such a way that it itself rotates and consequently with it also the telescope C^1 relatively to the slide carrier through the 80 same angle as the attachment bar B^1 . When this takes place, the connecting rod $J^1 J^2 J^3$ oscillates on the sleeve n^3 and the bolt N respectively in the direction of the arrow x^1 (see Fig. 6), and the rocking lever F oscillates relatively to the bar B in the direction of the arrow y^1 (see Fig. 6).

If, however, the initial velocity of the projectile has been diminished say by erosion of the barrel of the gun for example, the 90 guide piece G is moved by the gearing L g^2 in the guide f^1 in the direction of the arrow z (see Fig. 6), until the pointer g^3 is opposite the graduation mark of the graduation f^4 which corresponds to the diminished initial 95 velocity (see Fig. 8). The axis of the bolt g^1 then no longer coincides with the axis of the pins e^1 and e^2 , the result of which is that the gearing $F G g^1 H J^1 J^2 J^3$ augments the angular adjustment imparted 100 to the sighting telescope C^1 when the attachment bar B^1 is adjusted by an amount which corresponds to the diminished initial velocity. When the sighting telescope is adjusted to the angle corresponding to the 105 zero of the range graduation, this amount is itself equal to zero as the axis of curvature of the guide f^1 coincides with the axis of the bolt c^2 when the attachment bar B^1 is adjusted to correspond to the zero of the 110 range graduation, and increases with the increasing angle of adjustment.

In comparison with the apparatus of the first construction, the apparatus just described offers the advantage that the gearing 115 which is provided for making allowance for the influence of the diminished initial velocity, only executes oscillating movements when the sighting telescope has been adjusted. In consequence thereof the wear 120 and tear of this gearing is reduced to a minimum, and a permanently accurate adjustment of the sighting device insured.

If the trajectory of the projectile be altered by the use of another projectile or 125 another propelling charge, the bolt N and the length of the connecting rod $J^1 J^2 J^3$ is adjusted when the parts $B C H F G$ are in the position shown in Fig. 6, in a suitable manner by the aid of the above de- 130

scribed arrangement, and in particular and conveniently by means of scales and marks which are provided on the corresponding parts.

5 Claims.

1. A sighting device for ordnance mounted for movement with the gun which comprises a slide carrier, a pair of rods pivotally supported at one end thereof on said slide carrier, a sighting telescope carried by one of said rods, means for moving said rods to adjust the telescope, said means embodying a range device on the carrier and means independently adjustable of the carrier and embodying a sliding connection for operatively connecting the pivotally mounted rods.

2. A sighting device for ordnance which comprises a slide carrier, a pair of bars, means pivotally supporting said bars at one end thereof on said slide carrier so that they take part in the elevation of the gun barrel, a sighting telescope carried by one of said bars, adjusting means for the other bar, said adjusting means embodying a range device on said carrier, and means operatively connecting said bars to one another which embodies a connecting rod pivoted at one end to one of said bars, a rocking lever slidably supporting the other end of said connecting rod and means for adjusting said rocking lever to different angular positions with respect to said other bar, said connecting rod being connected by a second rod to the bar supporting means.

3. A sighting device for ordnance which comprises a slide carrier, a pair of bars pivotally supported at one end thereof, a sighting telescope carried by one of said bars, means supported on the slide carrier for adjusting the other of said bars to correspond to the desired range and means independently adjustable and embodying a sliding connection fixed on the other bar for imparting to the telescope carrying bar an additional correction which compensates for the erosion of the gun barrel.

4. A sighting device for ordnance which compromises a slide carrier for a gun, a bar pivotally mounted thereon at one end, a sighting telescope carried by the free end of said bar, a second bar pivotally supported at one end thereof, concentric with said first bar, means on the carrier embodying a range device for adjusting said second bar to correspond to the desired range, and means embodying a range correction device for operatively connecting said second bar to said telescope carrying bar, said means embodying a rocking lever carried by said second bar, a connecting rod secured to said first bar and having a sliding connection with said rocking lever, means for angularly adjusting said rocking lever and a second rod

connecting said first mentioned connecting rod to the slide carrier.

5. A sighting device for ordnance which comprises a gun slide carrier, a pair of bars pivotally supported at one end thereof, a sighting telescope carried by the free end of one of said bars, means for adjusting the other bar to correspond to the desired range, said means embodying a range indicating device, a range correction device operatively connecting said telescope bar to the other bar which embodies a rocking lever, a connecting rod adjustably connected to said rocking lever and pivotally secured to said telescope carrying bar and an adjustable connecting rod, connecting said rocking lever to the slide carrier.

6. A sighting device for ordnance which comprises a bar pivotally mounted on one end, means for fixing the sighting line on said bar, a second bar pivotally supported at one end thereof, concentric with said first bar, means embodying a range device for adjusting said second bar to correspond to the desired range, and means embodying a range correction device for operatively connecting said second bar to said first bar, said range correcting means comprising a rocking lever mounted on said second bar, a sliding piece mounted on said rocking lever, a connecting rod secured to said first bar and said sliding piece, a second rod connecting one of said range correcting means to a part of the gun which takes part in the elevation of the gun barrel and a gear inserted in the train comprising said second bar, the rocking lever and said sliding piece for adjusting one of the two last-named members relatively to the part on which it is mounted.

7. A sighting device for ordnance which comprises a bar pivotally mounted on one end, means for fixing the sighting line on said bar, a second bar pivotally supported at one end thereof, concentric with said first bar, means embodying a range device for adjusting said second bar to correspond to the desired range, and means embodying a range correction device for operatively connecting said second bar to said first bar, said range correcting means comprising a rocking lever mounted on said second bar, a sliding piece mounted on said rocking lever, a connecting rod secured to said first bar and said sliding piece, a second rod connecting said rocking lever to a part of the gun which takes part in the elevation of the gun barrel and a gear interposed between said sliding piece and the rocking lever for adjusting the sliding piece relatively to the rocking lever.

8. A sighting device for ordnance which comprises a bar pivotally mounted on one end, means for fixing the sighting line on said bar, a second bar pivotally supported at one end thereof, concentric with said first

- bar, means embodying a range device for adjusting said second bar to correspond to the desired range, and means embodying a range correction device for operatively connecting 5 said second bar to said first bar, said range correcting means comprising a rocking lever mounted on said second bar, a sliding piece mounted on said rocking lever, a connecting rod secured to said first bar and said sliding 10 piece, a second rod of adjustable length pivotally secured to one of said range correcting means and adjustably connected to a

part of the gun which takes part in the elevation of the gun barrel and a gear inserted in the train comprising said second bar, the 15 rocking lever and said sliding piece for adjusting one of the two last-named members relatively to the part on which it is mounted.

The foregoing specification signed at Es-
sen, Germany, this 15th day of June, 1920. 20
MAX BARTHOLDY.

In presence of—

HANS GOTTMANN,
JOSEF OLBERTZ.
